UNITED STATES PATENT OFFICE.

MILON J. TRUMBLE, OF LOS ANGELES, CALIFORNIA, ASSIGNOR OF ONE-THIRD TO
FRANCIS M. TOWNSEND AND ONE-THIRD TO ALFRED J. GUTZLER, BOTH OF LOS
ANGELES, CALIFORNIA.

CRUDE-PETROLEUM AND NATURAL-GAS SEPARATOR.

1,269,134.

Specification of Letters Patent. Patented June 11, 1918.

Application filed November 14, 1914. Serial No. 872,110.

To all whom it may concern:

Be it known that I, MILON J. TRUMBLE, a citizen of the United States, residing at Los Angeles, in the county of Los Angeles 5 and State of California, have invented a new and useful Crude-Petroleum and Natural-Gas Separator, of which the following is a specification.

My invention is designed to effect a 10 separation of natural gas from the crude oil when the same is first delivered from the well, and is also designed to accomplish the cleaning of the oil from free water and sand at the same time.

15 My invention is also adapted to overcome the unseating of the pump valve in an oil well when an excess of natural gas is present with the oil, thereby materially increasing the amount of oil produced from wells 20 where high pressure of gas exists.

My invention is also adapted to reduce the velocity and equalize the delivery of oil from wells in which the pressure of gas causes the oil to flow in gushes or by heads.

25 My invention is also effective in maintaining the lighter gravity series of the crude oil in combination with the heavier series of the oil, thereby producing from oil wells a product of lighter gravity than 30 where the oil and gas is permitted to separate on exposure to ordinary atmospheric conditions.

My invention consists in the arrangement and combinations of parts as hereinafter set 35 forth.

The accompanying drawings illustrate my invention and one method of its application:

Figure 1 is an elevation showing my invention as applied to an oil well, the velocity 40 reducing means and gas line being broken to contract the view.

Fig. 2 is a vertical section of the expansion chamber and fragment of velocity reducing means and oil heating means.

45 Fig. 3 is an inverted section of the expansion chamber taken on the line x^3-x^3 Fig. 3.

Fig. 4 is an enlarged vertical section of oil stopper for gas line.

50 Fig. 5 is an enlarged view of the oil outlet, the lower end of the outlet pipe and closure therefor being shown in section.

As shown in the drawings the expansion chamber 1 is provided with a tapering set-

tling chamber 2 which in turn communicates 55 with and is supported by a stand pipe 3. The top 4 of the chamber is centrally perforated and a T 5, having its stem 6 disposed horizontally, is arranged to register with the central perforation in the top 4. 60 Velocity reducing means, such as pipe 7, communicates with the horizontal stem 6 of the T 5 and delivers oil and gas into the interior of the chamber 1 through the vertical member 6a of the T. The velocity 65 reducing means 7, as shown, consists of a pipe many times greater in area than the oil pipe 8 which delivers the oil from the well 9.

A gas pipe 10 is arranged to lead the gas 70 from the upper end of the T 5, and connects with the gas collector within the expansion chamber, which will hereafter be explained. A gas pressure regulating valve 11 is provided in gas pipe 10 and controls 75 the passage of gas from the expansion chamber to any suitable receiver or destination.

Oil outlet means 12 is provided from the 80 chamber at a point intermediate the settling chamber of the expansion chamber and the oil inlet means. When the character of the oil demands, oil heating means may be provided such as the steam jacket 13 which surrounds the velocity reducer 7. A 85 steam pipe 14 is arranged to supply steam to such jacket. When desired a pipe 15 takes steam from the jacket 13 and delivers the same to a coil 16 arranged in the settling chamber 2 to further heat the oil with 90 in the chamber. The exhaust from the coil 16 is effected through pipe 17 which passes through the wall of the chamber.

A pump tube 18 having a sucker rod 19 is shown mounted on the casing head 20 of a 95 well 9. A gas pressure pipe 21 is shown as connecting the gas pipe 10 with the casing head of the well to apply the pressure of the gas within the expansion chamber to the top of the oil within the well 9 which 100 surrounds the pump tube 18. A valve 21a may be provided in the pressure pipe 21 to regulate the pressure within the well, or such valve may be dispensed with, in which event the pressure on the oil surrounding 105 the pump tube and the oil in the oil pipe 8 will be equalized.

Oil dividing means are provided interior

of the expansion chamber, such as cones 22 and 22^a. Preferably these dividing cones are spaced apart, one below the other, as shown, with their peripheries nearly in contact with the wall of the chamber. The oil 5 is delivered onto the upper surface of the cone 22 and spreads over the same evenly and is brought into contact with the wall 23 of the chamber and flows downwardly 10 thereover until it is collected in the settling chamber. The cone 22^a is provided as a supplemental spreader to insure the even distribution of the oil over the wall of the chamber. As shown in the form herein illustrated, the cones 22 and 22^a are supported 15 in the upper portion of the expansion chamber by means of gas collecting chamber 24 and pipe 25. Pipe 25 is screwed into flange 26 which in turn is seated upon and closes the upper end of the vertical member 6^a of the T 5, to which is connected the elbow 27 of the gas pipe 10. The lower end of the pipe 25 is screwed into a reducer 30, arranged with its larger end looking downward to receive the upper end of the gas 20 collecting chamber 24 which is open at its lower end 28. The gas collecting chamber is also provided with gas admitting ports 29, 29 and 29 arranged between the cones 22 and 22^a which are protected thereby to 25 prevent the entrance of oil into the gas line.

A valve seat 31 is provided in the reducer 30, and a valve stopper 32 is provided with means for seating the same when oil may 30 rise within the chamber to a point where it may gain access to the gas line 10. As shown, this stopper 32 comprises a flat circular body having a beveled edge adapted to fit the valve seat in the reducer, and is provided with a perforated shank 34 through which the float rod 35, actuated by 35 float 33, passes to open and close a vacuum breaker opening 36 in the stopper before actuating the stopper 32. A slot 38 is provided in the shank 34 which permits of the 40 passage of a pin therethrough and through the float rod to limit the movement of such rod in breaking the vacuum to permit the unseating of the stopper.

45 The movement of the stopper, float rod, and float, away from the valve seat is limited by the end of shank 34 coming into contact with a bracket 39. A bracket 40 is arranged near the bottom of the gas collecting chamber to guide the float rod 35.

50 A trapped oil outlet from the chamber is provided which consists of a submerged pipe 41 provided with a closure 42 which is actuated by means of a float 43 which is so 55 adjusted as to cause the pipe to be closed to the exit of oil before the level of oil reaches the open end of the pipe, to thereby prevent the escape of gas along with the outflowing oil from the chamber. Other forms 60 of traps will readily suggest themselves, but

the form herewith disclosed illustrates the function desired to be derived. A valve 44 is provided to permit sand and water to be drawn from stand pipe and settling chamber when desired. 70

It is to be remembered that an important feature of my invention is to provide means whereby the oil is divided into a thin or broken body whereby the gas may readily escape from its engagement therewith and 75 it is also desirable to maintain the oil in its divided form for a period of time sufficient for all the gas to free itself from the oil. It is also desirable to maintain the oil in a quiescent condition for a short period of 80 time within the settling chamber to permit sand and water to settle out of the same before the oil is drawn from the chamber.

In practice, oil is pumped from the well by actuating the sucker rod 19, which forces 85 the oil through the pipe 8 to the velocity reducer 7 from which it flows through the T 5 onto the top of the cone 22 by which it is spread over the wall of the expansion chamber and envelops the gas collector. 90 The oil may be heated while passing through the velocity reducer by means of the steam jacket 13 up to or about the boiling point of water. This heating will result in weakening the surface tension upon any water 95 contained in the oil and allows the same to settle in the bottom of the chamber. The settling of the water may be materially assisted by the pressure of the gas within the chamber, and, if necessary, more heat may 100 be applied to the oil by means of the steam coil 16.

In case oil is being taken from a well of the flowing type, and is intermittent in its heads, the velocity reducer will afford means 105 for equalizing the flow of oil into the expansion chamber. In case a large amount of oil should be delivered to the expansion chamber, and the egress thereof should be slower than the amount coming in, the float 110 33 will actuate the stopper 32 and close the gas outlet to prevent oil from getting into the gas line. The gas pressure will then increase and thereby force the oil from the chamber until the float will drop down 115 to open the gas line again. The pressure regulating valve 11 in the gas line 10 controls the exit of gas from the expansion chamber and thereby keeps a constant pressure on the oil within the chamber. 120

In the case of a wet gas, or a gas saturated with an oil of the lighter series, such as gasolene, it is desirable to maintain as high a pressure within the expansion chamber as may be practicable for the reason that 125 a large amount of such light series will thereby be compressed and remain with the oil. In some instances this action has resulted in producing an oil three points higher in gravity, according to the Baumé 130

scale, than had been produced by subjecting the oil and gas to the atmospheric action to permit the gas to escape. This increase in lightness of gravity brought the 5 producer an increase of price amounting to fifteen cents per barrel.

The admission of gas under pressure to the casing head of a well to equalize the pressure of gas within the pump tube, prevents the oil from slipping in the pump barrel on account of the valve being unseated by the upwardly flowing gas. This action 10 as produced by my invention increases the pumping efficiency and the production of 15 the well, thereby making profitable producers of wells that have theretofore been unprofitable.

The oil flowing from the expansion chamber through outlet 12 may be conducted to 20 any suitable tank or receptacle either by the pressure of the gas within the chamber or by gravity.

When desired, a safety valve may be provided for the chamber 1 to permit escape 25 of gas from the expansion chamber in the event that valve 32 should become stuck or remain seated on its seat. In some cases the float 33 and valve 32 may be dispensed with.

30 It will be noted that the action upon the oil while flowing down the wall of the expansion chamber in a thin film under pressure permits the free, dry, gas to readily escape therefrom, while the pressure exerted 35 upon the oil surface backed by the wall of the chamber holds the lighter liquids, such as gasolene, in combination with the oil body, and I desire to be understood as pointing out and claiming this action as being 40 of great benefit to the crude oil derived from the well on account of keeping the gasolene series in combination with the main body of oil.

I claim as my invention:

45 1. In an oil and gas separator, the combination of an expansion chamber arranged to receive oil and gas in its upper portion, means for spreading the oil over the wall of such chamber to flow downwardly thereover, 50 gas take-off means arranged to take off gas from within the flowing film of oil, an oil collecting chamber below the expansion chamber, an oil outlet from said collecting chamber, and valve controlled means arranged to maintain a submergence of the oil outlet.

55 2. In an oil and gas separator, the combination of an expansion chamber, inlet means arranged to permit the entrance of oil and gas into the chamber, means within the chamber adapted and arranged to distribute the oil over the wall of the chamber in a downwardly flowing film, gas take-off means arranged to take gas from within the 60 envelop of downwardly flowing oil, and

means for maintaining gas pressure upon such oil.

3. In an oil and gas separator, the combination of an expansion chamber having a surface adapted to sustain a flow of oil 70 thereover in a thin body, means for distributing oil onto such surface, pressure maintaining means arranged and adapted to maintain a pressure on one side of the flowing oil, withdrawing means arranged to 75 take gas from the chamber, and means for withdrawing oil from the chamber.

4. In an oil and gas separator, the combination of an expansion chamber, means for delivering oil and gas into the chamber, 80 means for maintaining pressure within the chamber, means for drawing oil from the chamber, and means within the chamber adapted to cause the oil to flow in a thin body for a distance to enable the gas contained and carried thereby to be given off 85 while the oil is subjected to pressure.

5. The combination in an oil and gas separator of an expansion chamber having a settling chamber communicating therewith, 90 means for delivering oil and gas into the upper portion of the expansion chamber, a cone arranged near the top of such chamber to receive the incoming oil and spread it over the wall of the chamber in a thin 95 film like form, a gas collector arranged below the cone, gas outlet means from such collector, a float controlled valve arranged to close the gas outlet means, means for drawing oil from the separator above the 100 settling chamber, and means for discharging sand or water from said settling chamber.

6. The combination in an oil and gas separator of an expansion chamber having a settling chamber communicating therewith, 105 means for delivering oil and gas to the chamber, oil spreading and dividing means arranged to receive the oil within the chamber and spread it in a thin film like form over the wall of the chamber to flow there- 110 down, gas collecting and outlet means arranged below the oil spreading means and within the flowing film of oil, a float controlled valve arranged to close the gas outlet when the oil rises to a predetermined 115 height within the expansion chamber, a float controlled valved outlet from the separator whereby a predetermined depth of oil is maintained in the settling chamber to sub- 120 merge the oil outlet and prevent the passage of gas therethrough and means for discharging sand or water from the settling chamber.

7. In a gas and oil separator, the combination of an expansion chamber, oil spreading means arranged within the chamber, oil supplying means arranged to deliver oil into such expansion chamber and onto the spreader means, gas collecting means arranged within the chamber, gas outlet means communicating with the gas 125 130

1. collecting means, oil outlet means from the expansion chamber arranged to draw oil from a point above the bottom thereof, such oil supplying means comprising an oil pipe 5 from a suitable oil supply and a velocity reducing means connected therewith, whereby the oil and gas are delivered to the expansion chamber in quiescent condition.
2. In an oil and gas separator, the combination of an expansion chamber, means within the chamber adapted to spread the oil in a thin film like form over the wall of the chamber, gas outlet means leading from the chamber, consisting of a gas pipe, 10 pressure regulating means arranged to control the passage of gas from the chamber through such gas pipe, oil outlet means arranged to draw oil from the expanding chamber, means to maintain such oil outlet means submerged within the body of oil in the chamber, velocity reducing means arranged to receive oil and gas from a source of oil supply and deliver the same into the expansion chamber, and means for heating 15 the oil within the velocity reducing device before its entry into the expansion chamber.
3. In an oil and gas separator, the combination of an expansion chamber having a centrally perforated top, a T arranged with 20 one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber 25 through the stem of the T, oil dividing means secured to the lower end of the last named gas pipe, and means for drawing oil from the chamber.
4. In an oil and gas separator, the combination of an expansion chamber having a centrally perforated top, a T arranged with 30 one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber 35 through the stem of the T, oil dividing means secured to the lower end of the last named gas pipe, and means for drawing oil from the chamber.
5. In an oil and gas separator, the combination of an expansion chamber having a centrally perforated top, a T arranged with 40 one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber 45 through the stem of the T, oil dividing means secured to the lower end of the last named gas pipe, and means for drawing oil from the chamber.
6. In an oil and gas separator, the combination of an expansion chamber having a centrally perforated top, a T arranged with 50 one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber 55 through the stem of the T, means for heating the oil during its passage to such chamber, oil dividing means secured to the lower end of the last named gas pipe, and means for drawing oil from the chamber.
7. In an oil and gas separator, the combination of an expansion chamber having a centrally perforated top, a T arranged with 60 one end of its cross to register with the central perforation in the top and having its stem disposed horizontally, a bushing on the upper end of the cross of the T, a gas pipe leading from such bushing, means for regulating the flow of gas from such expansion chamber through such gas pipe to maintain pressure within such chamber, a gas pipe depending from such bushing through the cross of the T and into the expanding 65 chamber, means for delivering oil to the chamber through the stem of the T, oil dividing means secured to the lower end of the last named gas pipe, and means for drawing oil from the chamber.
8. In an oil and gas separator, the combination of an expansion chamber, means within the chamber adapted to spread the oil in a thin film like form over the wall of the chamber, gas outlet means leading from the chamber, consisting of a gas pipe, pressure regulating means arranged to control the passage of gas from the chamber through such gas pipe, oil outlet means arranged to draw oil from the expanding chamber, means to maintain such oil outlet means submerged within the body of oil in the chamber, velocity reducing means arranged to receive oil and gas from a source of oil supply and deliver the same into the expansion chamber, and means for heating the oil within the velocity reducing device before its entry into the expansion chamber.
9. In an oil and gas separator, the combination of an expansion chamber having a centrally perforated top, a T arranged with one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber through the stem of the T, oil dividing means secured to the lower end of the last named gas pipe, and means for drawing oil from the chamber.
10. In an oil and gas separator, the combination of an expansion chamber having a centrally perforated top, a T arranged with one end of its cross to register with the central perforation in the top, and having its stem disposed horizontally, a bushing on the upper end of the cross of the T, a gas pipe leading from such bushing, a gas pipe depending from such bushing through the cross of the T and into the expansion chamber, means for delivering oil to the chamber through the stem of the T, means for heating the oil during its passage to such chamber, oil dividing means secured to the lower end of the last named gas pipe, and means for drawing oil from the chamber.
11. In an oil and gas separator, the combination of an expansion chamber having a centrally perforated top, a T arranged with one end of its cross to register with the central perforation in the top and having its stem disposed horizontally, a bushing on the upper end of the cross of the T, a gas pipe leading from such bushing, means for regulating the flow of gas from such expansion chamber through such gas pipe to maintain pressure within such chamber, a gas pipe depending from such bushing through the cross of the T and into the expanding chamber, means for delivering oil to the chamber through the stem of the T, oil dividing means secured to the lower end of the last named gas pipe, and means for drawing oil from the chamber.
12. In an oil and gas separator, the combination of an expansion chamber, a settling chamber communicating therewith adapted to receive the oil and retain the same in a quiet condition for a period of time, a stand pipe arranged to support the expansion chamber and settling chamber and to receive sand and water from the settling chamber, a submerged and trapped outlet for the oil arranged to draw oil from the separator, means for introducing oil into the expansion chamber, means adapted to divide the oil within the chamber, a gas outlet from the chamber, and means for preventing oil entering such gas outlet.
13. In an oil and gas separator, an expansion chamber; inlet means for feeding a foam composed of oil and gas through the central part of the top of said expansion chamber; an imperforate spreader cone, having its apex pointing upwardly, located inside said chamber in such a manner as to spread a thin film of oil over the inner wall of said chamber, and means for taking gas from the central portion of said chamber.
14. In an oil and gas separator, an expansion chamber; inlet means for feeding a foam composed of oil and gas through the central part of the top of said expansion chamber; an imperforate spreader cone, having its apex pointing upwardly, located inside said chamber in such a manner as to spread a thin film of oil over the inner wall of said chamber, and a gas outlet pipe supporting said cone and passing vertically upward through said inlet means, said pipe being arranged to take off gas from the apex of said cone.
15. In testimony whereof, I have hereunto set my hand at Los Angeles, California, this 9th day of November, 1914.
